THE JONES SAFETY TRAIN CONTROL SYSTEM COMPANY, OF BALTIMORE, MARY-
LAND, A CORPORATION OF MARYLAND.

ELECTRIC TRAIN-CONTROLLING DEVICE FOR RAILWAYS.

1,010,371.

Specification of Letters Patent. Patented Nov. 28, 1911.

Original application filed August 16, 1909, Serial No. 512,939. Divided and this application filed July 6, 1910. Serial No. 570,552.

To all whom it may concern:

Be it known that we, RICHARD T. JONES and FRANK T. JONES, citizens of the United States, residing at Baltimore, in the State of Maryland, have invented certain new and useful Improvements in Electric Train-Controlling Devices for Railways, of which the following is a specification.

This invention relates to improvements in electric train controlling device for railways.

One object of the invention is to provide an improved arrangement of cab mechanism and track circuits for controlling the operation of the air brakes on a train.

A further object is to provide an improved arrangement of track circuits including a third or short contact rail, whereby to substitute a track circuit on the cab when the track is clear to prevent the operation of the air brakes and by means of which in case a short circuit should by any means be established between the said third rail and the main rail on which the vehicle is traveling that an application of the brakes will be effected even though the block ahead is clear and thereby give notice that something is wrong.

With these and other objects in view the invention is illustrated in the accompanying drawing in which,—

Figure 1 shows diagrammatically a road bed and a complete set of mechanism and circuits for guarding the opposite ends of a block. Fig. 2 is a diagrammatic view of the track circuits and mechanism at the entrance to a block for actuating the air brakes, showing the same in condition to allow a train to proceed because the block ahead is clear, and Fig. 3, is a similar view but showing the mechanism in the operated position, as when the brakes are applied.

It is to be understood that the invention is applicable to either a double or single track road. In the diagrammatic view shown in Fig. 1, the mechanism is provided and arranged for a single track road.

In the drawings three block-sections, 1, 2, and, 3, are shown and the rails, 4, and, 5, of one block are insulated by suitable insulating material, 6, from the rails of the next block and each block is provided with a source of electricity such as suitable bat-

teries or other current supply as indicated by the numeral, 7.

As the system illustrated is that for a single track road both ends of each block must be provided with train controlling and signal devices, and by reference to Fig. 1 it will be seen that the mechanism for guarding trains traveling in one direction is located at one side of the track while that for guarding trains traveling in the other direction is arranged at the opposite side of the track.

In Fig. 1 a complete set of mechanism and wiring connections are shown for block, 2, one end of which is guarded by signal, 21, and the other end by signal, 22. The precise location of these two signals with respect to the two ends of block, 2, is immaterial but we prefer to locate them somewhere in the two blocks, 1, and, 3, adjoining the block they are to guard.

The system is operated under a normally closed circuit so that when a block is clear a circuit will be established through both rails, 4, and, 5, and the two signals, 21, and, 22, and said signals will be maintained in the safety position shown in Fig. 1. This circuit includes battery, 7, rail, 4, wire, 23, to signal, 21, then wire, 24, to signal, 22, wire, 25, to rail, 5, and back to said battery, 7. By means of the closed circuit the signals will be normally electrically maintained in the safety position and if for any reason the circuit should become broken both signals, 21, and, 22, will fall to the danger position.

The particular mechanism employed at each signal for operating the latter is immaterial and may be such as shown and described in pending application Serial Number 502,698 filed June 17th, 1909.

In addition to the two visual signals for the opposite ends of each block we also provide means for automatically operating the air-brakes on a train that proceeds regardless of the danger signal, and the ends of each block are guarded by this air-brake operating mechanism.

By again referring to Fig. 1 it will be noted the circuit which embraces the rails, 4, and, 5, of block, 2, also includes electromagnets, 26, near one end of the block and a similar magnet, 28, near the opposite end of the block. These two magnets have the

same function and produce the same results on trains approaching the block, 2, in either direction,—the function generally speaking being to effect a deenergization of a magnet 5 on the motor or locomotive and thereby release a valve that will cause a venting of the train line and thus apply the brakes.

The mechanism and connections hereinbefore described as coacting with block, 2, 10 is merely duplicated for each block but is not shown because it has not been practicable to illustrate all the mechanism coacting with blocks, 1, and, 3.

It has heretofore been explained that the 15 present invention includes an improved arrangement of mechanism and devices for automatically operating the air brakes on a train that approaches or enters a block, already occupied by a train. By reference 20 to Fig. 2 of the drawing this mechanism, which is carried on the motor or locomotive, will now be described.

The numeral, 40, designates the axle of the vehicle and, 41, the wheels thereof. An 25 air pipe, 42, on the vehicle is in communication with the train pipe or other portion of the air-brake system on the train and is provided with a valve, 43, having an arm, 44, which is normally held in the inoperative position 30 through a trip lever, 45, and an electro-magnet, 46, which controls the said trip lever by attracting it as long as the magnet is energized. A suitable support or bracket, 47, is carried by the vehicle and preferably 35 projects slightly at the side thereof so as to carry a contact shoe, 48, which may depend and brush over a short third or ramp rail, 49, adjacent the entrance to each block. The construction of this shoe and rail is not 40 essential to the present invention. A battery, 50, is provided on the vehicle for the purpose of normally, when the road is clear and the mechanism is in thorough working order, energizing the magnet, 46. A normal 45 circuit is formed on the vehicle which includes the battery, 50, the axle, 40; wire, 51; magnet, 46; wire, 52; contact shoe, 48, wire, 67, and back to the battery. By means of 50 this circuit the magnet, 46, remains energized so as to hold the valve-arm, 44, and trip lever, 45, in engagement and maintain the valve, 43, in the inoperative position while the track is clear and as long as the safety mechanisms are in proper order.

55 It is to be understood that the present apparatus in no way affects the usual manipulations of the air-brakes by the engineer through the engineer's brake valve and that the usual graduation, service and emergency 60 applications of the brakes may be made without regard to the mechanism here involved.

The construction of the contact shoe, 48, 65 is immaterial to the present invention and is shown and described in detail in our pend-

ing application Serial Number 512,939 filed August 16th, 1909 of which the present case is a division.

The function of the contact shoe, 48, is to wipe over the short ramp rail, 49, as the vehicle passes the latter and if the track ahead is clear to pick up the track circuit and throw it into temporary communication with the magnet, 46, on the vehicle while the normal vehicle circuit from battery, 50, is interrupted by the displacement of the shoe during its travel over said ramp rails, so as to keep the magnet energized and prevent the release of the arm, 45, and avoid an application of the brakes.

80 During the movement of a train through one block and toward another the visual signals will be automatically operated by the track circuits but as an extra precaution the automatic air-brake operating mechanism has been provided. It has been explained how the air-valve, 43, is maintained in the inoperative position by means of an electro-magnet, 46, on the vehicle and it has also been explained that the contact shoe, 48, is normally included in the circuit which keeps the said magnet energized. By reference therefore to Figs. 2 and 3 it will be seen that the wire, 52, forming part of the said circuit connects with the shoe and that a wire, 67, connects the shoe with the battery, 50, on the vehicle.

85 It has heretofore been explained that the circuit which includes the rails, 4, and, 5, also includes the electro-magnets, 26, and, 28, 90 near the opposite ends of each block. The mechanism coacting with and operated by these magnets is designed to effect an operation of the air-brakes under certain conditions and said mechanism will now be described, reference being made particularly to Figs. 2 and 3 of the drawings. The particular location of these magnets, 26, 28, with respect to the rails is immaterial, but whenever they may be placed they are designed to 95 control the operation of a lever, 68, which is pivoted so that one end will overbalance the other end,—the heavier end being located nearest the core of the magnet, while the lighter end thereof is provided with a down-turned portion, 69, which when in one position may project into a suitable receptacle, 70, containing a material which will act as an electric conductor, 71, such for example as mercury. It is to be understood that instead of employing a receptacle, 70, and mercury, 71, any other form of contact may be provided for the end, 69, of the lever. It will be noted that the wire, 23, included in the track circuit and connecting rail, 4, with 105 the signal, 21, also serves to pass a current through the magnet, 26, to energize the latter as long as the signal is in the safety position and the circuit is complete and so long as the said magnet is energized it will at- 115

120

125

130

135

tract the heavier end of the pivoted lever, 68, and hold it up against the magnet core and thereby keep the down-turned end, 69, of said lever in electrical contact with the material, 71. A wire, 72, electrically connects the material, 71, with the rail, 5, so as to prevent an operation of the brakes on the vehicle if the block ahead is clear, as will now be described. At suitable intervals along the road bed and adjacent the rails we provide short ramp rails, 49, which extend parallel with the main rails. These ramp rails are preferably located between the signal and that end of the block which the signal guards, and their position is such that the contact shoe, 48, on the vehicle may brush over and effect a momentary electrical contact with the same,—the shoe yielding and becoming bowed during its passage over the said rail. A wire, 74, connects the ramp rail with the wire, 23, of the track circuit at one side of the magnet, 26, while another wire, 75, connects said wire, 23, at the other side of the magnet with the pivoted lever, 68.

Supposing the block, 2, to be clear and a vehicle or train approaching the same through block, 1. The track circuit including the wires, 23, 24, and, 25, and the two signals, 21, and, 22, will be completed and 5 the signal arms held in the safety position. When the vehicle reaches the ramp rail, 49, (see Fig. 2) the contact shoe will ride up the inclined end of said rail and will be bowed as shown in said figure. This bowing 10 of the shoe will break the circuit from the battery, 50, on the vehicle. Before this circuit is broken however the shoe will pick up the track circuit from the ramp rail and pass the same through the magnet, 46, thus substituting the track circuit and prevent a 15 deenergization of said magnet, 46, and a consequent application of the brakes. This latter circuit will be as follows: from wire, 23, and wire, 75, to lever, 68; through the mercury, 71, and by wire, 72, to rail, 5; through wheel, 41, axle, 40, and wire, 51, to the magnet, 46; then by wire, 52, to contact shoe, 48, and finally from said contact shoe through ramp rail, 49, and wire, 74, back to track

wire, 23. It will therefore be seen that a 50 vehicle circuit it maintained on the vehicle while the latter is traveling in a block to energize the magnet, 46, and hold the brakes off but when a ramp rail is reached a track circuit is substituted and the magnet on the 55 vehicle is kept energized by the track circuit, provided the block ahead is clear. If on the other hand block, 2, is occupied and a train or vehicle passes the danger signal, 21, as shown in Fig. 3, the track circuit 60 through magnet, 26, will be broken and that magnet deenergized allowing the lever, 68, to drop and the end, 69, thereof to rise from the mercury and thus break the circuit at that point. By this means the wiping of the 65 shoe, 48, over the ramp rail, 49, would interrupt the circuit on the vehicle by breaking the circuit from battery, 50, and thus produce a deenergization of magnet, 46, on the vehicle and thereby release trip, 45, and 70 valve arm, 44, to apply the brakes.

Having thus described our invention what we claim and desire to secure by Letters Patent is,—

The combination with the two tracks or 75 rails having a plurality of blocks insulated from each other, of a ramp rail for each block; a vehicle having an air-brake valve, a magnet for controlling the same and a contact to engage the successive ramp 80 rails; an electric circuit including a battery for energizing the magnet on the vehicle while the latter is traveling between two ramp rails and a track circuit including another battery and also including means that 85 will send the current from the latter track circuit through the ramp rail to the contact on the vehicle to keep the magnet on the vehicle energized while the track ahead is clear and while the vehicle contact is on the 90 ramp rail.

In testimony whereof we affix our signatures in presence of two witnesses.

RICHARD T. JONES.
